ATTORNEY.

UNITED STATES PATENT OFFICE.

ANTHONY HESSELS, OF NEW YORK, N. Y.

EAR-RING.

SPECIFICATION forming part of Letters Patent No. 240,591, dated April 26, 1881.

Application filed December 1, 1880. (Model.)

To all whom it may concern:

Be it known that I, ANTHONY HESSELS, of the city, county, and State of New York, have invented certain new and useful Improvements 5 in Ear-Rings, of which the following is a specification.

This invention relates to improvements in diamond ear rings or drops, by which the same can be more conveniently attached to or removed from the ear; and the invention consists of a curved or angular bracket-arm, from which the setting is suspended, and of a spring puncture-hook, which is swiveled to the upper end of the bracket-arm and connected to the 15 lower end of the same, when the puncture-hook is passed through the lobe of the ear, by a catch-hook or other retaining device.

In the accompanying drawings, Figure 1 represents a sectional side elevation of my improved ear-ring, showing the puncture-hook thrown forward into position in which it is to be applied to the ear; and Fig. 2 is a side view of the same, shown as attached to the ear.

Similar letters of reference indicate corresponding parts.

In the drawings, A represents the setting of my ear ring or drop, which is hung by a fixed ring or eye, a, to a fixed ring, b, of the forward end of a curved or angular bracket-arm, B, that extends from a point above the setting down to a point back of the same. The bracket-arm B is provided at its upper front end with an ornamental rosette, d, and at its lower end with a catch-hook, e.

To the upper end of the bracket-arm B, preferably in front of the connection between the same and the setting, is swiveled the nearly-vertical end of the spring puncture-hook C, the lower free end of which may be sprung 40 into the catch e.

By releasing the spring puncture-hook C from the catch it may be swung around the setting until it arrives at a position in front of and in line with the bracket-arm B, as shown 45 in Fig. 1, in which position the puncture-hook is readily and conveniently passed through

the lobe of the ear, after which the bracket-arm and setting is turned back through an angle of one hundred and twenty degrees, and the lower spring end of the puncture-hook then 50 sprung into the catch at the lower end of the bracket-arm.

In removing the ear-ring the same operation, but in a reverse order, is accomplished, and in this manner the ear-ring put on or removed from the ear in a very convenient manner without the least annoyance, there being, furthermore, a reliable connection between the setting, bracket-arm, and puncture-hook.

I am aware that ear-rings in which the puncture-hook is connected by a swivel to the bracket-arm, or part from which the setting is suspended, have been used heretofore, and I therefore lay no claim, broadly, to ear-rings showing this feature.

Having thus described my invention, I claim as new and desire to secure by Letters Patent—

1. As an improvement in ear-rings, the combination, with a curved or angular bracket-arm, from which the setting is suspended, of a spring puncture-hook, the upper end of which is swiveled to the upper part of the bracket-arm, while the lower end is adapted to be sprung into a retaining device at the lower 75 end of the bracket-arm, substantially as and for the purpose set forth.

2. In ear-rings, the combination of a curved or angular bracket-arm, from which the setting is suspended, with a spring puncture-hook, 80 which is vertically swiveled by its upper end to the bracket-arm, and adapted to be swung into a position either in front or back of the setting, as described.

In testimony that I claim the foregoing as my invention I have signed my name, in presence of two witnesses, this 27th day of November, 1880.

ANTHONY HESSELS.
